US00D973146S

(12) **United States Design Patent** (10) **Patent No.:** **US D973,146 S**
Guo (45) **Date of Patent:** **** Dec. 20, 2022**

(54) **TOY**

(71) Applicant: **Guangdong Five stars Toys Co., Ltd.**,
Guangdong (CN)

(72) Inventor: **Shuzhong Guo**, Guangdong (CN)

(**) Term: **15 Years**

(21) Appl. No.: **29/836,084**

(22) Filed: **Apr. 25, 2022**

(30) **Foreign Application Priority Data**

Jan. 18, 2022 (CN) 202230033036.5

(51) **LOC (13) Cl.** **21-01**

(52) **U.S. Cl.**

USPC **D21/470**
